UNITED STATES PATENT OFFICE.

HARRY B. WHITE, OF CANTON, OHIO, ASSIGNOR TO THE GILLIAM MANUFACTURING COMPANY, OF CANTON, OHIO, A CORPORATION OF OHIO.

BOW SUPPORTING AND CLAMPING DEVICE.

1,279,194.

Specification of Letters Patent. Patented Sept. 17, 1918.

Application filed December 29, 1917. Serial No. 209,403.

To all whom it may concern:

Be it known that I, HARRY B. WHITE, a citizen of the United States, residing at Canton, in the county of Stark and State of Ohio, have invented a new and useful Improvement in Bow Supporting and Clamping Devices, of which the following is a specification.

This invention relates particularly to bow-supporting and clamping devices of a character suited for use on automobiles; and the primary object is to provide a device of this character, which is of improved construction, and operation.

The invention is illustrated, in the preferred embodiment thereof, in the accompanying drawings, in which—

Figure 1 represents a side (rear or front) elevational view of a bow-supporting and clamping device embodying the invention; Fig. 2, a vertical sectional view of the device in open condition, the section being taken as indicated at line 2 of Fig. 3; Fig. 3, a broken sectional view taken as indicated at line 3 of Fig. 1; Fig. 4, a bottom end view of the device; Fig. 5, a broken plan view; Fig. 6, a plan view showing the upper portion of the fixed arm or body-carried stock of the device; Fig. 7, an inner end view of the roller-equipped clamping lever employed; Fig. 8, an inner face view of the same; Fig. 9, a sectional view of the fixed bar, or stock, and the swinging clamping arm, the section being taken as indicated at line 9 of Fig. 1, and the view showing these parts before assembly; Fig. 10, a view of the pivot which connects the swinging arm to the stock, showing one end of the pivot deformed preparatory to casting same in the lower end of the stock; and Fig. 11, a broken vertical sectional view taken as indicated at line 11 of Fig. 1, this view showing the manner in which the pivotal connection between the stock and swinging arm is completed.

In the preferred embodiment, which is illustrated, A represents a fixed arm, or stock, equipped at an intermediate point with body-attaching means A¹; B, a swinging arm or bow-clamping member, having

its lower end pivotally connected with the 50 lower end of the stock A; and C, a clamping or securing lever pivotally mounted upon the upper end of the bow-clamping arm B, and adapted to secure the bow-clamping arm to the stock in the manner illustrated 55 in Fig. 1.

The principal parts of the device, which have been mentioned, are preferably formed from malleable cast iron.

The stock A is adapted to be secured to a 60 body-iron with which the automobile-body is equipped. The device A¹, for effecting this purpose, comprises a ring 1 cast integrally with either the rear or front surface of the arm A, and a set-screw 2 which extends through the wall of the ring, and is adapted to engage the body-iron which the bore 3 of the ring is adapted to receive. The bore 3 is provided at its inner side with a V-shaped recess, which is adapted to afford 70 bearings at the points 3^a. The inner end of the set-screw 2 is opposed to the V-shaped recess, so that the set-screw and the two points 3^a will afford a three-point bearing for a round iron entered in the opening 3. This construction is adapted to give a more secure connection with the body-iron than can be secured by using a round opening and a set-screw, which would afford only 75 a two-point contact, since the body-iron is 80 of necessity smaller than the opening 3.

Fig. 3 shows the front, or inner side of the stock A. The opposite side, which is adjacent the automobile body, may be termed 85 the back side of the stock.

The stock has at its lower end an outwardly-curved portion 4, equipped with an ear or pivot-lug 4^a, which, as appears from Figs. 4 and 9, is of approximately one-half of the thickness (from front to rear) of the 90 stock. In the ear 4^a is cast one end of a steel pivot-pin 5. The end of the pin 5 which is cast in the metal is deformed, as indicated at 5^a (Fig. 10), so that the pin will be more securely embedded in the metal. The deformities 5^a may be made in a punch-press, or in any suitable manner.

The swinging arm, or bow-clamping mem-

ber, B, has its lower end curved inwardly, as indicated at 6, and the portion 6 is provided with an eye, or perforated pivot-portion, 6^a, which matches the pivot-portion 4^a 5 and receives the pin, or pivot-stud, 5. The perforation 6^b in the pivot-lug 6^a may be cored in the casting operation. When the parts are brought together, they are readily secured in pivotal relation by upsetting the 10 projecting end of the pivot 5, as indicated at 5^b (Fig. 11).

The pivot-ear 4^a is equipped with a depending lug, or stop, 4^b, which is adapted to engage a shoulder 6^c (Fig. 2), with which 15 the part 6 is provided, thus limiting the outward swing of the bow-clamping member B.

The bow-clamping member B has its upper end-portion curved inwardly or toward the automobile-body, as indicated at 7, (Fig. 20 1); and this part is extended to provide a horizontal arm 7^a, which terminates in furcations 7^b, adapted to embrace the upper end of the stock A, and accommodate the clamping lever C.

25 The upper portion of the stock A is provided with a reduced extension 8, which preferably is tapered, as shown. The extension 8 is provided with a bearing surface, or track, 8^a, which preferably inclines forwardly and upwardly. The inner surface of the upper end of the stock is provided with a recess 8^b, in which is housed a leaf-spring 9. The spring 9 has its lower end-portion secured in the lower end of the recess 8^b by means of lugs 8^c, which are cast integrally with the stock, and which are bent in against the spring after the spring is inserted in the recess. The stock being of malleable iron, enables this expedient to be 35 40 employed as a means for securing the spring in its socket.

The spring 9 is provided some distance below its upper end with a projection 9^a, which is adapted to be engaged by a central 45 lug, or bearing, 7^c, with which the arm 7^a is equipped at the base of the slot between the furcations 7^b.

The clamping lever C preferably is a bell-crank lever comprising a main arm affording 50 a handle 10; a short arm comprising furcations 10^a; pivots 10^b which project outwardly from the furcations of the short arm, at the junction of the short arm with the arm 10; and an anti-friction roller 10^c, which 55 is journaled in the extremities of the furcations 10^a forming the short arm of the bell-crank-lever. The web 10^d between the furcations 10^a is cut away sufficiently to give adequate clearance to the roller, and also to 60 permit the extension 8 of the stock A to pass freely between the base-portions of the furcations in the closing operation.

The preferred manner of journaling the roller 10^c in the extremities of the furcations

10^a is to provide in the extremities of said 65 furcations slots which receive the reduced extensions, or journals, 10^e, of the roller. The casting, being malleable, enables the small lugs which form the walls of the small slots referred to, to be bent or closed about 70 the journals 10^e of the roller, so that the roller is thus effectively journaled in the furcations 10^a at very slight expense.

To enable the bell-crank lever C to be pivotally mounted in the furcations 7^b of the 75 swinging arm B, said furcations are provided with perforations which receive the pivots 10^b. The perforations are cored in casting the arm B. It will be noted that the furcations 10^a of the bell-crank lever C are 80 disposed between the furcations 7^b of the arm B (Fig. 5); the arm B being of malleable iron, enables the furcations 7^b to be spread apart sufficiently to enable the pivot-studs 10^b to be entered, whereupon the furcations 7^b are closed so as to embrace the furcations 10^a of the clamping lever C. It will be understood that in Fig. 2 the clamping lever C is not shown in section, so that the space between the furcations 10^a cannot 90 be seen in Fig. 2. However, as will be understood from Fig. 5, the space between the furcations 10^a is sufficient to enable the pivot-portions of the furcated bell-crank lever to pass freely the reduced extension 8 95 of the stock.

It will be understood from Fig. 1 that the curved lower end-portions 4 and 6 of the stock and the swinging arm coöperate to form a support for the lower bow of the 100 automobile top. The swinging arm may be of any desired form, of course. In the illustration given, the curved portions 6 and 7 are equipped with linings 11 and 12. The curvatures may be of such form as to partially 105 embrace the top and lower bows, if desired; and any suitable lining may be provided for the bow-clamping arm.

The manner of use of the device will be readily understood. Assuming the bow-supporting and clamping devices to be in the open condition illustrated in Fig. 2, the top may be clashed and the bows thereof will pass freely over the upper end of the stock-portions A. The swinging arm B may then 110 be swung inwardly and the clamping lever C may be turned about the pivots 10^b till the handle 10 assumes approximately a vertical standing position, with the roller 10^c engaging the back surface of the upper end of the 115 extension 8. The clamping lever C may then be swung toward the automobile-body and downwardly to bring the parts to the position shown in Fig. 1. It will be understood that the arm B may be actuated through 120 quite a wide range of movement by means of the clamping lever, which thus operates to draw the arm B up to a position parallel 125

with the stock A, and finally to effectually clamp the swinging arm to the fixed arm. In this operation, the anti-friction roller 10^c rolls down the inclined surface 8^a, and then 5 rolls upwardly again; and as the pressure becomes stronger, the upward bevel of the surface 8^a facilitates the actuation of the clamping lever. In the clamping action, the small projection, or bearing, 7^c, of the 10 arm B compresses the leaf-spring 9; and by the time the handle 10 of the clamping lever engages the rear surface of the stock A, as shown in Fig. 1, the axis of the roller 10^c has 15 passed above the dead center with reference to the pivots 10^b, so that any opening pressure exerted upon the bow-clamping arm B tends more effectually to lock the lever C.

When the top is in the elevated position, the bow-supporting and clamping device is, 20 nevertheless, secure against rattling, owing to the force exerted by the spring 9^a. Moreover, the depending handle 10 of the clamping lever tends to hold the parts in locked position, owing to the action of gravity upon 25 the bell-crank lever.

The device described is simple in construction, neat in appearance, and may be operated with great facility. It may be noted here that the operator, in swinging 30 the bell-crank lever C to the position shown in Fig. 1, may with his thumbs engage the top bow, and by a closing action of the fingers readily force the clamping lever to the locked position. The shape of the 35 handle 10, which projects past the stock in the manner shown in Fig. 3, facilitates this action. In the opening operation, the operator may support his hands on the upper bow, and by pressing his thumbs against the 40 projections of the handle, may force the bell-crank lever to the open position, the natural expansive force of the top aiding to throw the device open as soon as the roller 10^c has 45 passed below the dead center in the unlocking operation.

It is noteworthy that the range of movement of the swinging arm B under the drawing action of the clamping lever is approximately twice the radius of the short arm of 50 the bell-crank lever; also, that the use of an anti-friction member, or roller, enables the length of the actuating arm of the clamping lever to be reduced to a minimum. It is 55 noteworthy, also, that mounting the clamping lever on a backward extension of the upper end of the bow-clamping arm, enables the clamping lever to be disposed in the rear of the stock A and close to the automobile-body. This greatly enhances the 60 appearance of the bow-supporting and clamping device. The various details of construction which have been described facilitates the production of a device of neat appearance at very moderate cost.

The foregoing detailed description has 65 been given for clearness of understanding only, and no unnecessary limitations should be understood therefrom, but the appended claims should be construed as broadly as permissible, in view of the prior art. 70

What I regard as new, and desire to secure by Letters Patent, is:

1. In a device of the character set forth, the combination of a stock equipped with body-attaching means, a bow-clamping member having its lower end pivotally connected with the lower end of said stock and having its upper end equipped with a projection adapted to project past said stock, and a clamping-lever mounted on a transverse pivot carried by said projection and adapted to operate against the back surface of said stock and clampingly secure said clamping-member to said stock. 80

2. In a device of the character set forth, 85 the combination of a stock, a swingingly-mounted bow-clamping member carried thereby, and a bell-crank clamping-lever having its elbow-portion pivotally mounted on a transverse pivot carried by said bow- 90 clamping member and having an arm adapted to travel on the back surface of said stock.

3. In a device of the character set forth, the combination of a stock, having its upper end provided with a track surface, a swing- 95 ing bow-clamping arm pivotally connected with said stock and having its upper end equipped with an extension adapted to project past the stock, and a bell-crank lever mounted on a transverse pivot on said ex- 100 tension and having means adapted to move over said track surface.

4. In a device of the character set forth, the combination of a stock equipped with body-attaching means and provided at its 105 upper portion with a track surface, a bow-clamping arm having its lower end-portion pivotally connected with the lower end-portion of said stock and having its upper end-portion equipped with an extension adapted 110 to project past the upper end of said stock, and a clamping-lever mounted on said ex- 115 tension to swing in a plane parallel with the plane of said stock and bow-clamping arm and equipped with a roller adapted to travel longitudinally of said stock on said track surface.

5. In a device of the character set forth, the combination of a stock having its upper portion provided with a track, a bow-clamp- 120 ing arm pivotally connected to said stock, and a clamping-lever carried by said bow-clamping arm and adapted to swing in a plane parallel with the plane of said stock and bow-clamping arm and equipped with 125 anti-friction means adapted to travel on said track.

6. In a device of the character set forth,

the combination of a stock having its upper end equipped with a reduced extension, a bow-clamping arm pivotally connected to said stock and having a furcated extension 5 adapted to embrace the extension of said stock, and a clamping-lever pivotally mounted in said furcated extension.

7. In a device of the character set forth, the combination of a stock having its upper 10 end equipped with a reduced extension, a bow-clamping arm pivotally connected to said stock and having a furcated extension adapted to embrace the extension of said stock, and a clamping-lever pivoted in said 15 furcated extension and having a furcated arm equipped with an anti-friction member adapted to engage the extension of said stock.

8. In a device of the character set forth, 20 the combination of a stock having its upper end equipped with a reduced extension, a bow-clamping arm pivotally connected to said stock and having a furcated extension adapted to embrace the extension of said stock, and a bell-crank clamping-lever mounted in said furcated extension and having 25 a furcated arm equipped with an anti-friction member adapted to engage the extension of said stock.

9. In a device of the character set forth, 30 the combination of a stock equipped with body-attaching means, a bow-clamping arm pivotally mounted on said stock and having its upper end equipped with an extension 35 adapted to project back of the stock, and a bell-crank lever mounted on said extension and having a short arm adapted to engage the upper portion of the stock and a longer arm adapted to engage the back surface of 40 the stock at a lower point.

10. In a device of the character set forth, the combination of a stock equipped with body-attaching means, a swinging bow-clamping arm mounted on said stock, a bell-crank 45 clamping-lever adapted to engage the back surface of the stock, and means carried by the upper end of the bow-clamping member and including a transverse pivot serving to support said bell-crank clamping-lever.

11. In a device of the character set forth, 50 the combination of a stock equipped with body-attaching means and having its upper end provided with a forwardly and upwardly-inclined surface, a bow-clamping 55 arm pivotally connected with said stock, and a clamping-lever mounted on a transverse pivot on the upper end of said arm and having a member adapted to travel longitudinally on said inclined surface in the 60 clamping operation.

12. In a device of the character set forth, 65 the combination of a stock equipped with body-attaching means, a bow-clamping arm pivotally connected with said stock and hav-

ing its upper end equipped with an extension, a clamping-lever mounted on said extension and adapted to engage the back surface of said stock, and a spring interposed between said stock and extension, said spring tending to force said bow-clamping arm 70 away from said stock.

13. In a device of the character set forth, the combination of a stock equipped with body-attaching means, a spring mounted in the upper portion of said stock, a bow-clamping arm pivotally connected with said stock and equipped with an extension provided with a bearing adapted to press against said spring, and a clamping-lever 75 mounted on said extension and adapted to engage the back surface of the upper portion of said stock.

14. In a device of the character set forth, the combination of a stock equipped with body-attaching means, said stock having its 80 upper portion equipped on its front side with a spring and provided on its back side with a bearing surface, a bow-clamping arm pivotally connected with said stock and having its upper end provided with an extension 85 and having a bearing adapted to press against said spring, and a clamping-lever pivotally mounted on said extension and having a member adapted to travel on said bearing.

15. In a device of the character set forth, the combination of a stock, a bow-clamping lever pivotally mounted thereon, one of said members being provided at its upper portion with a recess and lugs adjacent said 100 recess, a spring confined in said recess and secured by said lugs, the other member having a bearing adapted to impinge against said spring, and a clamping-lever carried by one of said members and adapted to 105 force said members together against the resistance of said spring.

16. In a device of the character set forth, the combination of a stock equipped with body-attaching means and having its upper 110 end provided at its front surface with a recess, a leaf-spring secured in said recess, a bow-clamping arm having its lower end pivotally connected to the lower end of said stock and having its upper end equipped 115 with an extension provided with a bearing adapted to impinge against said spring, and a clamping-lever mounted on said extension and adapted to engage the back surface of the upper portion of said stock.

17. In a device of the character set forth, the combination of a stock equipped with body-attaching means, a bow-clamping arm having its lower end pivotally connected with the lower end of said stock, and a 125 clamping-lever supported on the upper end of said bow-clamping arm and disposed back of the upper end-portion of said stock.

in the closed position of the device, said clamping-lever comprising a bearing portion adapted to travel on the upper end of said stock and a wide handle-portion which projects past both the front and rear surfaces of the upper portion of the stock.

18. In a device of the character set forth, the combination of a pair of hingedly-con-

nected members adapted to confine the bows between them, a clamping-lever carried by one of said members and having a furcated portion provided with slots, and a roller having journals confined in said slots by the metal forming the walls thereof.

HARRY B. WHITE.
